MINE FUSE

Roy H. Bleikamp, Jr., St. Louis, Mo., assignor to Olin Mathieson Chemical Corporation, East Alton, Ill., a corporation of Virginia

Application November 5, 1957, Serial No. 695,478

2 Claims. (Cl. 102—8)

This invention relates to an improvement in a percussion type fuse and particularly in fuses for land mines.

Heretofore, certain types of explosive mines have included a fuse mechanism with a solid mechanical linkage including a dished resilient washer or spring disk of the Belleville type to effect explosion of the mine when it is run over by a vehicle, for example, as the mines lie either exposed or buried in the ground for concealment. Such constructions have had the disadvantage of requiring considerable height for the linkage and requiring placement of the mines at some particular orientation rather than placement at random orientation. Mines of this construction have had the further disadvantage of requiring that the ambulating target tread directly over the mine before explosion and destruction of the target would occur consistently. This limited the possibility of distributing such mines by strewing them upon the ground since they would then take a random orientation and most of them would be quite ineffective.

It is an object of this invention to provide a percussion type fuse relatively shallow and relatively free from directionality for land mines which will enable operation of the mines even when they are emplaced out of orientation with the direction of the line of application of the actuating pressure, either angularly or by separation. Another object is to provide a pressure sensitive fuse device for mines of relatively simple, small and economical construction. Still other objects and advantages will become obvious from a description of specific embodiments shown in the accompanying drawings in which:

Figure 1 is an elevational view in cross section of an embodiment shown prior to loading and of a type adapted for sub-surface emplacement;

Figure 2 is an elevational view in cross section of another embodiment shown loaded at the moment of firing and of a type adapted for surface emplacement; and

Figure 3 shows mines according to the embodiment of Figure 1 provided with a valve and prior to arming.

In accordance with this invention there is provided a fuse having a snap action element such as a dished resilient disk or washer arranged so as to be actuated by a fluid pressure element sensitive to exertion of an adjustable level of pressure over a relatively wide area applied at any one of various directions. A pneumatic or hydraulic motivating link instead of a solid linkage is contemplated.

The fluid pressure element includes a pliable protruding cap or dome and a captive pneumatic fluid enveloped between the snap element and the cap for acting on the snap action element. The element is specifically a washer of the Belleville spring type and may consist of spring metal but optionally consists of a suitable non-metallic plastic. Cellulose acetate, nylon, ethyl cellulose, polyvinyl acetate, polyvinyl chloride are suitable. This snap action element when of plastic is preferably of laminated fabric non-stretchable construction reinforced

2

by means of a suitable strand, fiber, or glass fabric material. The stiffness and uniformity of such a fabric construction tends to provide homogenous snap action. The Belleville spring element carries a firing pin normally in a position in which the pointed end of the firing pin is spaced from a primer charge for setting off the main blasting charge of the mine. The dome or bag member associated in sealing relationship with said washer member may consist of any suitable material but also preferably consists of some suitable plastic so as to avoid easy detection leading to disarming.

The fluid pressure actuating element may take various forms such as that of a captive fluid containing dome extending outwardly as an appendage from one side of the mine or it may take the form of a surrounding fluid enveloping bag. In any event, this shape makes possible actuation of the mine by pressures applied in other directions than that of the firing pin axis and along lines more displaced from the axis of movement of said firing pin. For adjustment of the arming and pressure levels of operation suitable for different weights of objects to be destroyed, a suitable valve may be provided. The valve may be advantageously located in the dome or cap, for example. It may be one or two way.

The dome or bag shaped closure member is in effect a fluid impervious membrane and consists of any suitable deflectable material of a composition, thickness, and/or shape characterized by less stretch and deflection than that available in the spring element, so that relative to the element the closure is unstretchable and deflectable to a lesser degree. Depending upon the mechanical design, size, operating pressure level, type of fluid employed (liquid or gas), and the predetermined sensitivity, the relative deflectability of closure and spring element is adjusted until satisfactory operation is attained at the predetermined pressure level.

The closure membrane consists of one of the suitable plastics such as plasticized polyvinyl acetate, silicone or nitrile rubber, polyethylene of suitable type and grade, and the like. In addition to these plastics, however, other plastics are contemplated for either the element or closure in attainment of the desired degree of deflectability.

With reference to the embodiment of Figure 1, the device includes a fuse body or casing 1 of polystyrene, the snap spring diaphragm 2 carrying the firing pin 3, and the motivating dome 4 of suitable plastic which together with the casing and diaphragm forms a fluid chamber in which there is enveloped the fluid 5 making a link between dome 4 and spring 2.

Casing 1 has two passageways in a T-arrangement, but only one of these passageways 9 which houses a detonator slide 10 is shown. The slide carries a stab-type detonator 11 and any suitable timing arrangement 12. One such arrangement consists of a suitable barrier and a vial containing a chemical which is released by impacting with the point 13 on slide stop plug 14 carried in the casing so that in the event that the fuse is not set off as intended after a suitable interim of time, the composition in vial 12 is released and finds its way through bore 15 of slide 10 to de-activate the fuse detonator 11. Passageway 9 also contains a compression slide spring 16 which puts the primer or detonator 11 into alignment with the firing pin 3 as shown as soon as the arming latch, carried in the other casing passageway athwart passageway 9, is pulled out of the arming latch striker opening 17 through slide 10 for central alignment with the cross passageway and its latch. Casing 1 also contains a major recess for holding the main explosive charge 20 ignitable through the thin casing partition 22 opposite firing pin 3, and also a minor recess 21 which is a relief well alignable with the detona-

tor 11 when the fuse latch still projects into striker opening 17 to allow harmless venting upon premature firing for any reason when spring 16 is compressed and the fuse not armed. Charge 20 is covered by plate 25.

Slide bore 15, latch opening 17, together with the clearance between plug 14 and casing 1 vents one side of spring diaphragm 2 through outer casing vent 23 so as to permit proper fluid operation of the fuse system of the dome 4, fluid link 5 and spring 2 all suitably sealed.

Casing 1 is provided with a guard such as ring 24 so as to prevent any likelihood of a mechanical connection between snap spring 2 and dome 4 should the latter be collapsed abnormally.

In the embodiment of Figure 2, the fuse casing 1 is substantially identical with that of the previous embodiment, but the fluid link motivating membrane takes the shape of a substantially fuse surrounding fluid enveloping bag 40 having an external configuration such as to give bag 40 the appearance of some naturally occurring object such as a stone or piece of timber. This embodiment has a vent 33 functioning similarly to the vent 23 of Figure 1. It will be appreciated that the embodiment of Figure 2 is suitable for surface emplacement while the embodiment of Figure 1 is more suitable for the type of mine which is buried.

In operation these embodiments are quite similar except for differences in pressure levels at which the fuse ignites the explosive charge; and, therefore, operation will be described in connection with Figure 1.

In the position shown an arming plunger in the cross passageway not shown pulls a slide latch out of the opening 17 which allows the slide 10 acting under the bias of spring 16 to move to the armed position shown in Figure 1 with the detonator 11 under the firing pin 3 and over the explosive base charge 20. Movement of the slide 10 also causes point 13 of plug 14 to pierce the timing arrangement 12. Thus fully armed, the fuse is responsive to any pressure on the pressure dome 4 which creates a pressure in fluid 5 acting on the snap spring 2 to flex it and drive the pin 3 into the detonator 11 thereby initiating the mine.

This dome is designed to safely carry a minimum load and any load in excess of this will pressurize the fluid at a predetermined pressure level before the spring element 2 goes into operation quickly to drive firing pin 3 into firing engagement and thus explode the mine. It will be appreciated that an incompressible liquid will provide a more sensitive arrangement operable over a narrower range of pressures whereas a gas is operable over a wider range of pressures because of its compressibility.

The pressure level of operation will be effected not only by the construction of the snap spring 2 but also by the construction of the dome 4 or bag 40 and by the volume and type of fluid 5 enveloped. The condition of the latter will effect the level of operation so that a

valve provides advantages for certain purposes. As shown in Figure 3, a valve 50 may be located in the motivating dome 4. The valve may be of the one-way type so that the domes of the devices may be collapsed making for compact storage. Upon release the domes snap out into position and the trapped atmosphere provides the fluid link. With the two-way valve other variations are possible such as evacuation to provide a further safety factor since under this condition spring 2 is withdrawn, dome 4 is collapsed to virtual inoperability and the fluid link 5 is very weak. Another modification is to pressurize the device at above atmospheric pressures.

It will be understood that the foregoing embodiments now believed preferred are intended to be illustrative and not to limit the invention except as set forth in the claims, and that other changes and modifications may occur to those skilled in the art within the spirit and scope of the invention as set forth in the appended claims.

20 What is claimed is:

1. A mine comprising a casing containing an explosive charge, a stab initiated primer mounted on said casing, an imperforate Belleville spring mounted within said casing and having a firing pin secured thereto within the periphery of said spring, said pin normally held in spaced relationship with respect to said primer, said periphery being secured in sealing relationship with respect to said casing, and a substantially dimensionally stable, flexible protuberant closure sealingly secured to said casing, said casing, spring and closure forming therebetween an envelope, said envelope being substantially completely filled with a single body of captive fluid, said fluid forming a positive fluid pressure link between said closure and spring, said closure being deflectable under pressure applied externally from any direction, thereby reducing the volume of the envelope and increasing the pressure of said fluid therein upon said spring to deflect said spring and snap it beyond its equilibrium position for driving said firing pin into said primer.

2. The mine of claim 1 wherein the closure is a dome-shaped member of substantially dimensionally stable, flexible plastic material from the group including plasticized polyvinyl acetate, a silicone rubber, nitrile rubber, and polyethylene.
